BOMB RELEASING SHACKLE

Roscoe I. Markey and David Herman, East Orange, and Robert Schaefer, Irvington, N. J., assignors to Pollak Manufacturing Company, Arlington, N. J., a corporation of New Jersey

Application January 20, 1942, Serial No. 427,432

6 Claims. (Cl. 89—1.5)

The invention relates to bomb releasing shackles, particularly adapted for use with aerial bombs.

The present invention has to do with the arming of the bomb. In dropping aerial bombs it oftentimes happens the bombs must be dropped unarmed. This would be the case where due to some injury to the plane and it becomes necessary to lighten the load either to travel a greater distance or prior to making an emergency landing. Should this occur over friendly territory the bombs must be dropped so they will not explode. At other times it is desired to drop the bombs so they will explode on impact. At such a time the fuse in the head of the bomb is armed. At other times it is desired to drop the bombs so they will not explode on impact but will penetrate before exploding. Under these conditions the bombs would be dropped with their head fuses unarmed and the tail fuses armed. The tail fuses being time fuses the bombs will therefore penetrate before exploding.

The principal object of the present invention is to provide a device of extreme simplicity for accomplishing the foregoing.

In accordance with the present invention it is preferred to use electrical means for operation. However another object and advantage is to provide a manually operated means of operation in case anything went wrong with the electrically operated means.

A further object is to arrange the parts as a single unit so that if any of the individual parts were injured the entire unit could be easily and quickly removed from the shackle and a new one substituted.

Other objects and advantages will become apparent as this specification proceeds. Referring to the drawings forming a part thereof and in which a preferred form of the invention is illustrated:

Fig. 1 is a side elevation of the bomb releasing shackle;

Fig. 2 is a side elevation of the arming unit removed from the shackle;

Fig. 3 is a fragmentary elevational view partly in section showing the position of the parts when electrically operated to drop the bomb with the tail fuse armed and the head fuse safe or unarmed;

Fig. 4 is a fragmentary elevational view partly in section showing the position of the parts when electrically operated to drop the bomb with the head fuse armed and the tail fuse safe or unarmed;

Fig. 5 is an elevational view partly in section showing the position of the parts when the bomb has been dropped safe or unarmed;

Fig. 6 is an elevational view partly in section showing the position of the parts when the arming unit has been manually operated to drop the bomb with the tail fuse armed and the head fuse safe or unarmed;

Fig. 7 is an elevational view partly in section showing the position of the parts when the arming unit has been manually operated to drop the bomb with both the tail fuse and head fuse armed;

Fig. 8 is a longitudinal section through one of the solenoids; and

Fig. 9 is a cross sectional view taken on line 9—9 of Fig. 8.

Referring again to said drawings the framework or supporting structure of the shackle comprises a pair of spaced plates 10—10 resistance welded or otherwise secured to a channel member 11.

Hooks 12 and 13 are pivoted at 14 and 15 in the plates 10. In the closed or locked position 25 of the hooks their open ends abut studs 16 carried by the plates 10 and confine the rings or other suitable members 17 which carry the bomb (not shown), thus providing a two point support for the bomb.

The upper portions of the hooks 12 and 13 are pivoted at 18 to a longitudinally extending tie member 19. It will be apparent the hooks 12 and 13 and the tie member 19 are movable simultaneously, and furthermore the weight of the 35 bomb as it hangs on the hooks tends to move the tie member toward the left and cause the hooks to move away from the studs 16 to release the bomb.

Releasable locking means for the tie member 40 and its hooks are provided and fragmentary parts of this mechanism are indicated by the reference numeral 20. However this releasable locking means is subject matter of a copending application and further illustration or description 45 thereof is not necessary in this application. Means indicated generally by the reference numeral 21 are provided for dropping the bomb armed or safe and this means will now be described.

As heretofore stated the means for dropping the bomb armed or safe is built into a single removable unit and this unit, removed from the shackle, is illustrated in Fig. 2. It is generally U-shaped in cross section and is provided with 55 openings 22 through which bolts or pins 23 pass

to hold the unit between the side plates 10 of the shackle. The pins 23 are preferably made with a push fit to expedite their removal.

A pair of solenoids 24 and 25 are mounted between the sides 26 of the supporting member and are held in place by rivets 27. One of the solenoids is shown in detail in Figs. 8 and 9. It comprises the winding 28, core 29 and pin 30. A spring 31 urges the pin 30 against the core 29 and when the solenoid is not energized the pin is in its retracted position as shown in Fig. 8. It will be apparent that immediately upon the solenoid being energized the core 29 will be pulled within the coil and the pin 30 projected.

Under the solenoids 24 and 25 retainers 32 and 33 are mounted on pins 34. Each of the retainers has a flattened side 35, a toe 36 and a slot 37 for the reception of one end of a spring 38. The other ends of the springs 38 engage the bottom wall of the supporting member and thus the retainer 32 is urged in a counterclockwise direction and the retainer 33 is a clockwise direction. The retainers are also provided with ears 39, the purpose of which will hereinafter be apparent. Fingers 40 are mounted on or formed as part of the supporting member and these fingers in conjunction with the toes 36 function either to retain the arming wires 41 and 42 or permit them to drop with the bomb.

The electrical means of operation will now be described. When it is desired to drop the bombs safe or unarmed neither solenoid 24 or 25 is energized, the release mechanism is operated and the arming wires 41 and 42 move the retainers against the light spring 38 and the arming wires drop with the bomb as illustrated in Fig. 5.

Fig. 3 illustrates the position of the parts when it is desired to drop the bomb with the tail fuse armed. The solenoid 24 has been energized and its pin 30 projected in which position it engages the ear or shoulder 39 of the retainer 32 and prevents clockwise movement of the retainer 32. The arming wire 41 is retained by the toe 36 and finger 40 and the bomb drops with the tail fuse armed. The retainer 33 is free to be moved by the arming wire 42 which drops with the bomb and the head fuse is unarmed.

Fig. 4 illustrates the position of the parts when it is desired to drop the bomb with the head fuse armed. It will be noted the solenoid 25 has been energized and its pin 30 projected thus preventing movement of the retainer 33 and holding the arming wire 42 in the shackle as described in connection with Fig. 3. At times it might be desired to drop the bomb with both head and tail fuses armed and it is thought to be apparent this could readily be accomplished by energizing both solenoids.

If for any reason the electrically operated means should fail it is important to provide manually operated means for controlling the arming unit and this means will now be described.

A tube 50 is mounted in the supporting member between the solenoids 24 and 25 and extends downwardly between the retainers 31 and 32. The tube is provided with slots 51 and 52 into which both retainers may enter as shown in Fig. 5 when it is desired to drop the bomb safe or unarmed.

To prevent rotation of the tube 50 and to act as a guide a pin 53 passes through the tube and its ends are slidably mounted in slots 54 in the sides 26 of the supporting member. Means are provided for longitudinally moving the tube 50

and this means comprises a pull loop 55, the upper end of which extends above the shackle and the lower end of which is suitably secured to the pin 53. A suitable fitting 56 acts as a spacer and is resistance welded to the side plates 26 to stabilize the tube 50. A spring 57 surrounding the pull loop and confined between the top of the shackle and the fitting 56 returns the tube to its normal position.

The manual operation will now be described. It will be noted the slot 51 is shorter than the slot 52. Fig. 6 illustrates the position of the parts when dropping the bomb with the tail fuse armed and the head fuse unarmed. The tube 50 has been raised slightly from the position of Fig. 5 and the flat 35 on the retainer 32 engages the solid part of the tube thus preventing the toe 36 from moving away from the finger 40 and holding the arming wire 41 in the shackle. The slot 52 being longer than the slot 50 the retainer 33 is free to move and the arming wire 42 drops with the bomb.

Fig. 7 shows the arrangement of the parts with the bomb being dropped with both the head and tail fuses armed. The tube 50 has been raised a sufficient amount so that its solid part prevents movement of both retainers and both arming wires 41 and 42 are held in the shackle when the bomb is dropped. With the manual control as now arranged the bomb cannot be dropped with only the head fuse armed but this is of no great moment because when the bomb is dropped with both fuses armed if for any reason the head fuse did not function on impact the time fuse in the tail then would function.

Throughout the specification and claims the device is spoken of as a shackle. It is thought to be obvious the arming unit is just as applicable to a bomb rack or any device for releasing bombs.

A switch 60 is also carried by the supporting member. A contact finger 61 is engaged by the hook 12 to operate the switch. The switch might function to close a circuit to an adjoining bomb shackle or to give a signal in the bombardier's station.

Changes in details of construction and arrangements of parts such as would occur to one skilled in the art are to be considered as coming within the spirit of the invention as set forth in the appended claims.

We claim:

1. In combination with means for dropping a bomb having two arming wires, an arming unit, a supporting structure for said arming unit, arming wire retainer members pivoted in said supporting structure, a pair of solenoids mounted in said supporting structure, means actuated by the plunger of said solenoids for engaging and locking the retainer members in arming-wire holding position when the plunger are extended, resilient means for normally maintaining the plunger in their retracted position, means for urging the retainer members to their wire holding position, the energizing of said solenoids causing the plunger to be extended to lock the retainer members in wire holding position and drop the bomb armed, and when said solenoids are not energized the arming wires will move the retainer members and the bomb may drop safe or unarmed, and manually controlled means slidably mounted for longitudinal movement between said solenoids and said retainer members and having oppositely disposed surfaces to block move-

ment of said retainer members and oppositely disposed relieved portions to allow movement of said retainer members, one of said relieved portions being longer than the other for engagement with said retainer members whereby one or both of said retainer members may cause the arming wires of said bomb to be retained by said arming unit.

2. In combination with means for dropping a bomb having two arming wires, an arming unit, a supporting structure for said arming unit, arming wire retainer members pivoted in said supporting structure, a pair of solenoids mounted in said supporting structure, means actuated by the plungers of said solenoids for locking the retainer members in arming wire holding position when the plungers are extended, resilient means for normally maintaining the plungers in their retracted position, means for urging the retainer members to their wire holding position, the energizing of said solenoids causing the plungers to be extended to lock the retainer members in wire holding position and drop the bomb armed, and when said solenoids are not energized the arming wires will move the retainer members and the bomb may drop safe or unarmed, a longitudinally movable member positioned between said retainer members, slots in said longitudinally movable member, and means for manually moving said longitudinally movable member, said slots in the normal position of said longitudinally movable member permitting both of said retainer members to enter therein to permit free movement of said retainer members, the movement of said longitudinally movable member to one position causing one of said retainer members to hold one of said arming wires in said arming unit, and the movement of said longitudinally movable member to another position causing both of said retainer members to hold both of said arming wires in said arming unit.

3. In combination with means for dropping a bomb having two arming wires, an arming unit, a supporting structure for said arming unit, a pair of arming wire retainer members pivoted in said supporting structure, a pair of solenoids, one for each of said arming wire retainer members, pins actuated by the cores of said solenoids to engage the retainer members and lock them in arming wire holding position when the solenoids are energized and the pins are projected, spring means for normally maintaining the solenoid cores and their pins in the retracted position, and spring means for urging the retainer members to their wire holding positions, the energizing of said solenoids causing the pins to be projected in the path of the retainer members to lock the retainer members in arming wire holding position and drop the bomb armed, and

when said solenoids are not energized the arming wires may move the retainer members and the bomb may drop safe or unarmed.

4. In combination with means for dropping a bomb having two arming wires, a frame, two oppositely disposed retainer members pivoted on said frame, said members having outwardly extending wire retaining hooks and flattened surfaces located at substantially right angles to said hooks, a slidably mounted member located between said retainer members, said slidably mounted member having straight parallel surfaces located closely adjacent said flat surfaces on said retainer members, and being formed with two oppositely disposed slots located in the plane of the retainer members and arranged in overlapping relationship in the direction of the movement of the member, the slots being of a size to receive a portion of the retainer members and to permit the retainer members to pivot to release positions when brought opposite thereto, and resilient means for urging said retainer members toward their wire holding positions.
5. In combination with means for dropping a bomb having two arming wires, a supporting frame, two retainer members pivoted in said frame, said members having outwardly extending wire retaining hooks and ears formed thereon, a pair of solenoids mounted in said supporting frame above said retainer members, pins actuated by the cores of said solenoids for engaging said ears on said retainer members to lock them in arming wire holding position when the solenoids are energized and the pins are projected, spring means for normally retaining the solenoid cores and their pins in the retracted position, and spring means for urging the retainer members to their wire holding positions.
6. In combination with means for dropping a bomb, an arming unit having two retainer members for two arming wires, said retainer members being mounted for movement toward each other to release the arming wires and constructed with means actuated by the arming wires to effect such movement, a longitudinally movable member positioned between said retainer members, said longitudinally movable member having oppositely disposed surfaces to block movement of said retainer members, and oppositely disposed relieved portions to allow movement of said retainer members, one of said relieved portions being longer than the other whereby one or both of said retainer members may cause the arming wires to be retained by said arming unit.
